HIGH-LEVERAGE TOOL

Albert G. Daniels, Winnsboro, S.C., assignor, by mesne assignments, to James R. Kearney Corporation, St. Louis, Mo., a corporation of Delaware

Filed Sept. 19, 1958, Ser. No. 762,011

1 Claim. (Cl. 30—187)

This invention concerns high-leverage tools and particularly tools of the type in which a pair of dies or cutters are brought together with considerable force to effectuate a forming or cutting operation on metal objects of very heavy gauge. The simplicity and great mechanical advantage of my tool makes it particularly suitable for use as a hand tool for field work in the electrical industry, but the principle of the tool is applicable equally well to power driven tools for any use in which high-leverage is desirable.

High-leverage tools which employ either gear-reduction principles, a principle of cam action, or a lever principle are well known in the art; but as far as I am aware, the unique combination of gear-reduction, cam, and lever action in a single mechanical power transmission taught herein has not previously been used. In addition, my gear-cam-lever arrangement has the advantage that the tool may be easily preset by hand to the point where the forming or cutting jaws engage the work-piece, without the necessity of turning the operating crank; that the depth of the cut or the extent of deformation is easily and accurately adjustable; and that when the cutting or forming operation is completed, the tool will automatically snap back into a position where it is ready to begin the next forming or cutting operation.

It is therefore an object of my invention to provide a simple high-leverage forming or cutting tool which achieves a maximum mechanical advantage with a minimum of parts.

It is a further object of my invention to provide a high-leverage tool in which the point of beginning of the closing operation can be easily and rapidly set by hand to accommodate work-pieces of varying sizes.

It is a still further object of my invention to provide a simple high-leverage mechanism which will automatically reset itself to its starting position at the end of each operation.

It is still another object of my invention to provide a high-leverage tool in which the amount of maximum closure of the jaws is easily and accurately adjustable.

It is finally yet another object of my invention to provide a high-leverage mechanism in which the average theoretical mechanical advantage can be varied in a predetermined pattern throughout its cycle of operation.

Other features of the invention will be in part apparent from and in part pointed out in the following detailed description taken in connection with the accompanying drawings, in which:

Fig. 1 is a side view of a hand tool manufactured according to my invention;

Fig. 2 is a top view of the same tool;

Fig. 3 is a side view of an alternative embodiment of the tool of my invention suitable for both manual and mechanical operation;

Fig. 4 is a top view of the tool shown in Fig. 3;

Fig. 5 shows the force distribution in a conventional gear train;

2

Fig. 6 shows the effect of using a conventional gear train in the tool of Figs. 1 through 4;

Fig. 7 shows a type of gear train suitable for use in the tool of Figs. 1 through 4;

Fig. 8 shows an alternative type of gear train also suitable for use in the tool of Figs. 1 through 4; and

Fig. 9 is a detail of the cam-and-roller arrangement of Figs. 1 through 4.

Basically the tool of my invention consists of a pair of jaws which may carry any desired cutting or forming head. Each jaw tapers at its base into an elongate arm, the two arms being journaled between a pair of rigid cross-members in such a fashion that the portions of the arms extending on the opposite side of the cross-members from the heads constitute a pair of levers to provide a first mechanical advantage. A spring is provided to pull the lever portions of the arms together so as to bias the jaws of the tool into the open position. In the operation of the tool, the jaws are closed against the spring bias by rotating a pinion, the axis of which is operatively fixed with respect to the first jaw, against the toothed surface of a generally spiral-shaped cam which is rotatably attached to the lever operating the second jaw. This arrangement takes advantage not only of the maximum leverage available, but it also has the further advantage that the amount of mechanical advantage provided by the tool (i.e. the ratio between the force exerted by the operator on the tool and the force exerted by the tool on the workpiece) at any given aperture of the jaws is readily predeterminable by the appropriate shaping of the cam, as will hereinafter appear.

The shape of the cam is so designed that when it reaches a pre-set position (e.g. when the jaws are completely closed), the pinion will ride over the edge of the cam, whereupon the jaws will open under the action of the spring and the pinion will again engage the cam at the point of maximum aperture of the jaws.

If it is desired to partially close the jaws before beginning the cutting or forming operation, the leverage of the lever arms makes it possible to pull the supporting arms apart by hand and then to spin the cam until it engages the pinion. The same effect can be obtained by providing a ratchet between the operating crank and the pinion, so that the cam and pinion may be reversely rotated by hand without the necessity of moving the operating crank. The drop-off face of the cam provides a highly suitable surface to be engaged by the operator's finger in accomplishing this process.

An interesting feature of my invention is the fact that the average theoretical mechanical advantage of my tool (taking the distance travelled by the crank handle when the pinion is turned through the arc between two adjacent teeth as one unit) at any given point during the closing operation can be pre-set at will by appropriate shaping of the cam. This results from the fact that the amount of travel of the jaws for the arc of the pinion lying between the apex of one tooth and the apex of the next is directly proportional to the increase in distance between the axis of rotation of the cam and the bottom of the grooves on the cam periphery which the above-mentioned adjoining teeth of the pinion engage (Fig. 9). In other words, if the amount of travel of the jaws corresponding to a rotation of the pinion from the apex of one tooth (A in Fig. 9) to the apex of the next (B in Fig. 9) is designated as $1/M$, then

$$M = \frac{k}{dr}$$

k being a constant of proportionality and dr the increase in radius of the cam from the bottom of the groove engaging tooth A to the bottom of the groove engaging tooth B. The "bite" of my tool is not uniform through

out the closing cycle for reasons discussed hereafter. It reaches a maximum while the apex of a tooth of the pinion is in engagement with the bottom of the corresponding groove of the cam, and it drops to zero between the maxima. The term "average theoretical mechanical advantage" as used herein is the value M , i.e. the average ratio of pinion rotation to jaw travel during a single cutting stroke, i.e. between two adjacent teeth of the cam. For example, by shaping the cam so that the distance from the center of its axis of rotation to the bottom of the groove of the cam increases considerably from groove to groove in the early portion of the travel of the pinion, comparatively little during the median part of its travel, and considerably again toward the end of its travel, the tool can be made to bite relatively quickly (low average theoretical mechanical advantage) in the beginning of its cutting cycle when the object to be cut is still readily deformable, slower but with more force (higher average theoretical mechanical advantage) in the median part of the cut where the workpiece opposes the maximum resistance, and quickly again at the end of the cutting cycle where portions of the workpiece (such as the outer strands of a stranded wire) are already cut and offer no more resistance. On the other hand, of course, it is possible to shape the cam in such a manner that the average theoretical mechanical advantage of the tool remains uniform throughout the cutting cycle, or in any other way that might be desirable under any practical conditions that may be encountered.

It will be readily apparent from the preceding paragraph that the force exerted between the pinion and the cam is predominantly a compressive force acting perpendicularly to the peripheries of the pinion and the cam at the point of contact, rather than a tangential turning force as is encountered in a conventional gear train. It is therefore, necessary to provide gear teeth of such a configuration that the compressive force is absorbed by the tooth in a direction perpendicular to the peripheries of the pinion and the cam. A preferred embodiment of a pinion and cam meeting this requirement is shown in Figure 7 and will be discussed hereafter.

Referring now to Fig. 1, the tool of my invention is generally shown at 10. The tool 10 is provided with a handle 12 which may be of any suitable shape. Extending upwardly from the handle 12 is a member 14 on which are mounted a shaft 16 carrying the pinion 18 and the operating crank 20, and a shaft 22 on which is journaled the lever arm portion 24 of the first jaw 26. A set screw 28 equipped with a lock is provided to permit adjustment of the jaw 26 with respect to member 14. This adjustment makes it possible to set the degree of closure of the jaws at which the pinion 18 will ride over the edge of the cam 32. The cam 32 is provided with a smooth drop-off face 34 and with gear teeth 36 along the remainder of its periphery. The cam 32 is journaled on a shaft 38 mounted at the end of lever portion 40 of the second jaw 42. The jaws 26 and 42 are journaled respectively on shafts 44 and 46 which are mounted in the rigid cross-members 48. A pair of springs 50 connects the lever portion 40 of jaw 42 with the member 14 so that the force exerted by the spring 50 is transmitted through the cross-members 48 and causes the lever portion 24 of jaw 26 to rest firmly against set screw 28.

The pinion 18 is turned by the crank 20 which is equipped at its outer end with a handle 52, and which may embody a ratchet 54 biased by a spring 56 so as to provide a rigid connection between crank 20 and pinion 18 when the crank 20 is turned clockwise, but to disengage the connection between 18 and 20 when the crank 20 is turned in the counterclockwise direction.

In the alternative embodiment shown in Figs. 3 and 4, the basic structure of the jaws 26 and 42 and of their operating mechanism has been retained. In addition, however, a gear box 58 has been mounted on the arm portion 24 of jaw 26. A handle 60 is fixedly attached to

the gear box 58. The pinion 18 in this embodiment is keyed to the shaft 16 and is driven by a gear 62 also keyed to shaft 16. A pinion 64 engages gear 62, and pinion 64 is driven by shaft 66 to which it is keyed. 5 Shaft 66 in turn can be rotated by one of two means: for manual operation, a crank 68 may be attached to the fitting 70 keyed to shaft 66, or for motor driven operation, shaft 66 can be rotated by a gear 72 keyed to it, the gear 72 being in turn driven by pinion 74 attached to shaft 76 which protrudes from the gear box 58 and may be engaged by the chuck 78 of any appropriate power drive means, as illustrated schematically at 80.

Figs. 5, 6, 7, and 8 illustrate a problem encountered in the design of the gear teeth of the pinion and cam, and some possible solutions therefor. An enlarged view of a conventional gear train is shown in Fig. 5. It will be noted that the active stress 82-84 of the gear teeth takes place in a direction almost tangential to the gears. If the useful force to be transmitted is a tangential rotational one, the total active stress 82-84 on the gear teeth is $f_t \sec \phi$, which is only slightly greater than the useful tangential force f_t . In my high-leverage system, however, the useful force is substantially radial, the tangential component being negligible as far as the active stress is concerned. Consequently, if conventional gear teeth were used in my system (Fig. 6), the active stress 82-84 on each side of tooth 86 would be

$$\frac{f_p}{2} \cosec \phi$$

30 Clearly, the resulting wedge action would soon wear out or break even the strongest teeth. Consequently, it is necessary to shape the teeth of my pinion and cam in such a manner (Fig. 7) that each tooth 86 of the pinion presents a large area of contact to the corresponding groove 88 in the cam while contacting the portion 90 of the groove 88 in which the tooth 86 is lifted by the increased radius of the cam. The portion 90 of the groove 88 is so shaped as to have a generally tangential curved surface which espouses the complementarily shaped apex of tooth 86 at the critical point of maximum force transmission.

35 Comparatively little force is exerted on the pinion and cam during all phases of their rotation other than the phase during which the lifting of tooth 86 by portion 90 of groove 88 actually effects a cutting or forming stroke. Therefore, and in order to prevent overriding of the gears during the "idle" phase of the turning motion, the teeth may be shaped as shown in Fig. 8, where the numeral 90 again designates the active lifting portion of groove 88, and 92 designates a substantially radial surface of groove 88 which is engaged by tooth 86 during the "idle" rotational phase of the movement of the pinion and cam.

40 Obviously, other shapes of teeth satisfying the basic requirement of effective force transmission without excessive strain on the teeth may be used on the pinion and cam, and the above description is not intended to be exhaustive of the subject, but rather to be illustrative of some practical embodiments of my invention.

45 In operation, a workpiece is positioned between the jaws 26 and 42 and the jaws are closed upon the workpiece by manually rotating cam 32 in a counterclockwise direction until the jaws engage the workpiece. The crank 50 (or the appropriate motive means in the alternative embodiment of Figs. 3 and 4) is then turned so as to impart a clockwise motion to pinion 18. Pinion 18 engages the toothed edge 36 of cam 32 and thereby causes cam 32 to rotate in a counterclockwise direction. This rotation of cam 32 about shaft 38 causes the point of engagement of pinion 18 with the edge 36 of cam 32 to become increasingly spaced from the shaft 38, thus causing the arm portions 40 and 24 to separate, which in turn causes the jaws 26 and 42 to come together. As 55 explained previously herein, the instantaneous speed of

closing of the jaws 26 and 42 at any given point for any given constant speed of pinion 18 is predetermined by the shape of the cam 32. When the jaws have reached the position predetermined by the setting of the set screw 28, the pinion 18 will ride off the end of the toothed portion of 36 of cam 32 and will slide along the smooth face 34 of cam 36 to its original position as the arm portions 24 and 40 are drawn together under the influence of spring 50, thus opening the jaws. The tool is thereupon instantly ready for positioning about the next workpiece and repeating the operation.

It will be seen from the above description that I have provided a simple and highly efficient high-leverage tool which combines in a single simple and rugged mechanism all the advantages of a gear reducer, cam drive, and lever. In addition, my tool has the advantage that the amount of maximum closure of the jaws can be readily and accurately adjusted by a single set screw to suit the necessities of the work, and that the jaws can easily and quickly be closed into contact with the workpiece by hand so as to avoid any unnecessary turning of the operating crank. The use of a ratchet between the crank and the pinion further makes possible the operation of the tool in close quarters where complete rotation of the crank is not feasible. My tool also has the desirable feature that the average theoretical mechanical advantage of the tool may be continuously changed as the jaws close upon the workpiece, so as, for example, to close relatively quickly while little pressure is required at the beginning of the operation, and to increase the pressure exerted upon the workpiece at the expense of speed as the resistance of the workpiece against deformation increases. Finally, the fact that all the operating parts of my tool are freely movable with respect to each other makes my tool highly impervious to mechanical damage or abuse, particularly where the gear teeth and the adjustment of the jaws are concerned.

It will be readily understood that the embodiments described above are merely illustrative, and that my invention may be embodied in numerous different forms

for different uses. For example, if it were desired to limit the pressure exertable on the workpiece, the gear engagement between the pinion and the spiral cam may be replaced by a friction engagement such as might be obtained, for example, by making the surface of the pinion and the periphery of the cam smooth and coating them with rubber or other suitable materials. Also, by mechanical expedients such as, for example, mounting jaw 42 on arm 24 and jaw 26 on arm 40, in the manner of an ordinary pair of pliers, my tool may be used as a spreading tool rather than a compression tool. Finally, the power drive means may be permanently incorporated into the tool, rather than a separate unit as described herein. I therefore do not wish to limit myself by the above description, but only by the scope of the following claim.

Having thus described the invention, what is claimed and described to be secured by Letters Patent is:

A high-leverage tool comprising a pair of jaws carrying working heads adapted to engage a workpiece, said jaws being mounted for movement with respect to each other, each of said jaws having an arm portion, a lever member forming a continuation of one of said arm portions, a pivot between said arm portion and said lever member, stop means for limiting the rotation of said lever member on said arm portion of said first of said jaws, a spiral-shaped cam rotatably mounted on the arm portion of the other of said jaws, and drive means mounted on said lever member and engaging the periphery of said spiral-shaped cam to impart rotation thereto.
